UNITED STATES PATENT OFFICE.

CHARLES A. HULTQUIST, OF LOS ANGELES, CALIFORNIA.

ROCK-DRILL.

1,077,913

Specification of Letters Patent.

Patented Nov. 4, 1913.

Application filed February 5, 1913. Serial No. 746,662.

To all whom it may concern:

Be it known that I, CHARLES A. HULTQUIST, a citizen of the United States, residing at Los Angeles, in the county of Los Angeles and State of California, have invented new and useful Improvements in Rock-Drills, of which the following is a specification.

This invention relates to rock drills operated by compressed air, steam, or other motive fluid, and the main object of the invention is to prevent fluttering or rearward movement of the valve and to insure full and proper opening and closing of the ports.

15 In a previous patent of mine, No. 978,586, dated December 13th, 1910, I have shown a rock drill the valve of which contained a controlling plunger formed with a neck of reduced size in its center portion, and a 20 further object of the present invention is to avoid the use of such reduced neck and thereby facilitate the work of construction and improve the operation.

In carrying out my invention I employ 25 separate plungers in the valve for controlling it and by the use of these separate plungers I minimize the possibility of leakage in addition to securing the foregoing advantages.

30 Referring to the drawings: Figure 1 is a longitudinal section through the drill, showing the piston at a point slightly beyond the center of its backward movement, with the valve in corresponding position, the section being taken on line x^1-x^1 , Fig. 2. Fig. 2 is a horizontal section on line x^2-x^2 , Fig. 1. Fig. 3 is an end elevation. Fig. 4 is a plan view of the sleeve. Fig. 5 is an enlarged section through the valve on the same plane as Fig. 1. Fig. 6 is a view similar to Fig. 1, showing the piston at a further point in its rearward stroke and the valve having moved partially to the right. Fig. 7 is a view similar to Fig. 1, showing the piston at the extreme right and the valve at the extreme right in position to admit operating fluid at the back end of the piston to cause the piston to move forwardly. Fig. 8 is a section on line x^8-x^8 , Fig. 5.

45 The drill comprises a cylinder 1 in which is a piston 2. The cylinder has ports 3 and 4 which communicate with a valve chamber 5. The valve chamber 5 has a steel lining sleeve 6 shown in detail in Fig. 4, and plugs 50 7 and 8 are screwed in opposite ends of the

valve chamber 5. Motive fluid is introduced through a swivel 9 which has a shoulder 10 operating in a bearing formed in one end of the valve chamber 5 and being formed in one end of the valve chamber 5 and being 60 formed with a recess 11 which has a bearing on a non-revolvable block 12, which is mounted in a lug 13 and retained by a bolt 14 which is screwed into the head of the plug 8 and has a tapered shank portion 15 fitting 65 in the block 12. I have found in practice that operators of the drill are apt to employ too much force in screwing up the bolt which controls the action of the swivel and with the present construction when the bolt 70 14 is turned to tighten the swivel, the conical portion 15 will wedge and bind in the block 12, thereby interposing a very considerable resistance to further turning of the bolt, thus obviating straining of the bolt and resultant breakage. Where the bolt is screwed up too tightly, the constant vibration of the 75 drill causes crystallization and breakage of the bolt which is avoided by this construction.

80 The sleeve has a central supply port a and on one side thereof, a cylinder port b and an exhaust port c , and on the other side thereof a cylinder port b' and an exhaust port c' . These ports may be considered as extending 85 circumferentially around the sleeve, although in fact they are segments on account of solid portions 16 which act as necessary bridges to retain the sleeve as one piece. In each end of the sleeve are perforations 17 90 for allowing fluid to enter behind the valve from ports k , k' . Valve chamber 5 is formed with annular grooves 18 registering with the respective ports in the sleeve in order to provide a circumferential communication of 95 the air throughout each series of port segments in the sleeve.

Slidable within the sleeve 6 is a valve 19 which has a central circumferential groove d and end grooves e and e' . The valve has 100 recesses f , f' in each end thereof and in the recesses f , f' are plungers g and g' . Leading from passage f to the surface of the valve on the opposite side of groove d is a passage h and leading from recess f' to the 105 surface of the valve on the opposite side of groove d is a passage h' . The outer portions of passages h and h' are bridged as shown in Fig. 8 in order to insure an opening for the ports h or h' . Thus if there were only one 110

port h' it might happen at some time to lie next to one of the bridging portions 16 which would close communication through the port. In each end the valve is provided 5 with a series of ports 20 for draining leakage as will be described. The valve also at each end has a port 21 leading from passage e and e' to the outer end of the valve.

The cylinder 1 is provided with ports i , i' 10 located at intermediate points and adapted to be covered and uncovered by the piston in its movement. These ports are connected by passages j , j' with ports k , k' formed in the valve chamber at each end thereof and 15 with which the ports 17 communicate.

Operation is as follows: Referring to Fig. 1, the valve 19 is at its extreme throw to the left and lies against plug 7, while plunger g is at the extreme right against plug 8. In 20 this position the plunger recess f' is in communication through passage h' with cylinder port b , valve port e and exhaust port c so that there is no pressure tending to move the valve to the right, while the other plunger recess f is in communication through port h with cylinder port b' and through valve port d with supply port a so that the air pressure thus admitted to this plunger chamber holds the valve to the left until the 25 proper time comes for it to move. Fluid is at this time flowing into the cylinder at port 3, through valve port d and supply port a and causing the piston 2 to move to the right in the direction of the arrow. As 30 the piston continues moving in this direction, its front end uncovers port i' , whereupon pressure from behind the piston will flow through passage j' to the space 7^b at the left of the valve 19 and although there 35 is pressure in plunger recess f tending to hold the valve to the left, it will be noted that this pressure at f is only that amount which is exerted against the area of the inner wall of the recess f , while the pressure in 40 recess 7^b is equal to the combined area of the valve 19 including the area of the end of the plunger g' and therefore overbalances the pressure in recess f and commences to move the valve to the right, also moving 45 plunger g' . When the valve 19 has thus moved past the center of its travel at which time the piston 2 is near the end of its stroke, the parts being in the position shown in Fig. 6, the exhaust of the cylinder at 50 the port 4 is cut off by the valve which has moved its port e out of communication with passage 4 and at the same time partially opened communication between the passage 4 and supply port a , and the supply of fluid 55 to the cylinder through the passage 3 is cut off because valve port d which is in communication with the supply has moved out of communication with passage 3, and passage 3 is just coming into communication 60 with exhaust port c' through valve port e' with exhaust port c'

and also plunger recess f through passage h is in communication with cylinder port b' and thence directly with valve port e' and exhaust port c' . At the point designated x the valve is admitting fluid to the cylinder 70 through the passage 4 and through the medium of annular cylinder port b and passage h' to the plunger recess f' and the pressure therein moves plunger g' to the left, causing it to travel in the opposite 75 direction to that in which the valve is now traveling, for at this time the valve has not yet entirely moved to the right. The valve will continue traveling to the right because at this time plunger recess f is open to 80 exhaust and pressure in the plunger recess f' is sufficient, the proportions being such that the valve will complete its movement to the right at the same time the plunger g' has been moved back against plug 7 to the 85 left, this position of the parts being shown in Fig. 7, and the pressures in the respective chambers f and f' hold the valve 19 alternately against the plugs until the proper time comes for it to move and thus prevents 90 all rebounding or fluttering of the valve. The parts having reached the position shown in Fig. 7, the space at the left of the piston is in communication with the exhaust through passage 3, port e' and exhaust port c' , while fluid pressure is entering through passage 4 from valve port d and supply port a , whereupon the same operation takes place in reverse order to that 95 which has just been described.

The perforations 20 are for draining out any leakage that might occur from plunger recesses f or f' along the plungers g and g' should the latter become worn, the leakage passing through perforations 20 into exhausts c , c' . If this leakage were not taken care of, pressure would pile up behind the valve in the recesses f and f' which would interfere with the action of the valve. The 100 perforations 21 which are of minute size are to take care of any leakage that might come from the cylinder through the passages j or j' .

It will be seen that this construction prevents fluttering or rebound of the valve when it strikes the plugs 7 or 8 and that rockers, tappets or auxiliary valves are eliminated, the valve being moved by fluid pressure. The fluid which is utilized for moving the valve is first used in the cylinder for moving the piston. The valve and plunger are reversible and the fluid pressure not operating on the valve, is effective over the full area of the valve which assures positive operation of the valve. The plugs 7 and 8 are removable so that the valve can be removed from either end of the valve chamber.

What I claim is:

1. In a rock drill, a cylinder, a piston 130

therein, a valve chamber, a valve in said chamber, said valve having plunger recesses in opposite ends, plungers in said recesses and movable with respect to the valve chamber to allow air pressure to act on the combined area of a plunger and the valve, ports between said valve and cylinder for the admission and exhaust of fluid to and from the cylinder, said ports being controlled by said valve; said valve having passages leading to the respective plunger recesses and adapted to be moved into or out of communication with the cylinder ports, said cylinder having valve ports with passages leading from the ports to the valve chamber for operating said valve, and said valve ports being opened and closed by the movement of the piston.

2. In a rock drill, a cylinder, a piston therein, a valve chamber; a valve in said chamber, said valve having a central circumferential groove and a circumferential groove on each side thereof, thereby forming two end flanges and two center flanges, the valve being formed with plunger recesses in opposite ends thereof, a plunger in each recess, the valve having passages leading from the respective plunger recesses to points on the respective surfaces of the center flanges, the cylinder having ports for the inlet and exhaust of fluid to operate the piston, said ports being controlled by said valve, said cylinder also having valve ports with passages leading from the respective ports to the opposite ends of the valve chamber, and said valve ports being located at intermediate points of the cylinder and being opened and closed by the movement of the piston.

40 3. In a rock drill, a cylinder, a piston therein, a valve chamber, a valve therein, ports for the inlet and exhaust of fluid to and from the cylinder to operate the piston, said ports being controlled by said valve, said valve having plunger recesses in opposite ends, plungers in said recesses and movable with respect to the valve chamber to allow air pressure to act on the combined area of a plunger and the valve, and means controlled by the movement of the piston for admitting fluid to the valve chamber at each end of the valve, and for admitting fluid to the interior of said plunger recesses.

45 4. In a rock drill, a cylinder, a piston therein, a valve chamber, a valve therein, the cylinder having ports for the inlet and exhaust of fluid to and from the cylinder to operate the piston, said valve chamber having circumferential cylinder ports communicating with the respective latter ports and having a circumferential supply port between said cylinder ports and having circumferential exhaust ports on the outer side of the cylinder ports, said valve being formed with two end flanges and two center

flanges, thereby providing a center circumferential groove and two end circumferential grooves, said valve being formed with plunger recesses in opposite ends thereof and having passages leading from the respective plunger recesses to points on the outer surface of the center flanges of the valve, and plungers in said recesses, said cylinder having valve ports at intermediate points with passages leading from said ports to the ends of the valve chamber.

5. In a rock drill, a cylinder, a piston therein, a valve chamber, a valve therein, the cylinder having ports for the inlet and exhaust of fluid to and from the cylinder to operate the piston, said valve chamber having circumferential cylinder ports communicating with the respective latter ports and having a circumferential supply port between said cylinder ports and having circumferential exhaust ports on the outer side of the cylinder ports, said valve being formed with two end flanges and two center flanges, thereby providing a center circumferential groove and two end circumferential grooves, said valve being formed with plunger recesses in opposite ends thereof and having passages leading from the respective plunger recesses to points on the outer surface of the center flanges of the valve, plungers in said recesses, said cylinder having valve ports at intermediate points with passages leading from said ports to the ends of the valve chamber, and a sleeve lining in said valve chamber having segmental port openings which register with the said circumferential ports in the valve chamber.

6. In a rock drill, a cylinder, a piston therein, a valve chamber, a valve therein, the cylinder having ports for the inlet and exhaust of fluid to and from the cylinder to operate the piston, said valve chamber having circumferential cylinder ports communicating with the respective latter ports and having a circumferential supply port between said cylinder ports and having circumferential exhaust ports on the outer side of the cylinder ports, said valve being formed with two end flanges and two center flanges, thereby providing a center circumferential groove and two end circumferential grooves, said valve being formed with plunger recesses in opposite ends thereof and having passages leading from the respective plunger recesses to points on the outer surface of the center flanges of the valve, plungers in said recesses, said cylinder having valve ports at intermediate points with passages leading from said ports to the ends of the valve chamber, and a sleeve lining in said valve chamber having segmental port openings which register with the said circumferential ports in the valve chamber, said passages in said valve being

branched to insure communication between a passage and a segmental port in said sleeve lining.

7. In a rock drill, a cylinder, a piston therein, a valve chamber, a valve therein, the cylinder having ports for the inlet and exhaust of fluid to and from the cylinder to operate the piston, said valve chamber having circumferential cylinder ports communicating with the respective latter ports and having a circumferential supply port between said cylinder ports and having circumferential exhaust ports on the outer side of the cylinder ports, said valve being formed with two end flanges and two center flanges, thereby providing a center circumferential groove and two end circumferential grooves, said valve being formed with plunger recesses in opposite ends thereof and having passages leading from the respective plunger recesses to points on the outer surface of the center flanges of the valve, plungers in said recesses, said cylinder having valve ports at intermediate points with passages leading from said ports to the ends of the valve chamber, and a sleeve lining in said valve chamber having segmental port openings which register with the said circumferential ports in the valve chamber, the valve chamber having circumferential grooves near its ends for receiving air from the cylinder, said sleeve lining having perforations near each end which communicate with said latter grooves.

8. In a rock drill, a cylinder, a piston therein, a valve chamber, a valve therein, the cylinder having ports for the inlet and exhaust of fluid to and from the cylinder to operate the piston, said valve chamber having circumferential cylinder ports communicating with the respective latter ports and having a circumferential supply port between said cylinder ports and having circumferential exhaust ports on the outer side of the cylinder ports, said valve being formed with two end flanges and two center flanges, thereby providing a center circumferential groove and two end circumferential grooves, said valve being formed with plunger recesses in opposite ends thereof and having passages leading from the respective plunger recesses to points on the outer surface of the center flanges of the valve, plungers in said recesses, said cylinder having valve ports at intermediate points with passages leading from said ports to the ends of the valve chamber, and a sleeve lining in said valve chamber having segmental port openings which register with the said circumferential ports in the valve chamber, the valve chamber having circumferential grooves near its ends for receiving air from the cylinder, said sleeve lining having perforations near each end which communicate with said latter grooves.

openings which register with the said circumferential ports in the valve chamber, 60 said valve having radial perforations from the plunger recesses to the outer grooves of the valve and each end flange of the valve having a longitudinal perforation extending therethrough.

9. In a rock drill, a cylinder, a piston therein, a valve chamber, a valve therein, ports between the valve chamber and cylinder controlled by said valve, plugs in the opposite ends of the valve chamber with 70 projections extending into the valve chamber, said valve having plunger recesses in its ends, plungers in said recesses, their outer ends adapted to bear against said plug projections and movable with respect to the 75 valve chamber to allow air pressure to act on the combined area of a plunger and the valve, means controlled by the piston for regulating the admission of air to and from the ends of the valve, said plungers controlling the operation of the valve.

10. In a rock drill, a cylinder, a piston therein, the cylinder having ports leading to the interior of the cylinder, a valve chamber, a valve therein controlling the passage 85 of fluid through said ports, plugs screwed in opposite ends of the valve chamber, the drill having a lug, a bushing in said lug, forming a bearing, said bushing having a conical recess, the end of the valve chamber 90 forming a bearing, a swivel journaled on said bearing, and a bolt extending through said bushing and screwed in the end of one of said plugs, said bolt having a tapered portion fitting the conical recess in the bushing. 95

11. In a rock drill, a cylinder, a piston therein, the cylinder having ports leading to the interior of the cylinder, a valve chamber, a valve therein controlling the passage of fluid through said ports, the drill having 100 a lug, a bushing in said lug forming a bearing, said bushing having a conical recess, the end of the valve chamber forming a bearing, a swivel journaled on said bearing and a bolt extending through said bushing and 105 screwed in the head of said valve chamber, said bolt having a tapered portion fitting the conical recess in the bushing.

In testimony whereof, I have hereunto set my hand at Los Angeles, California, this 30 110 day of January, 1913.

CHARLES A. HULTQUIST.
